UNITED STATES PATENT OFFICE.

HAROLD W. GOFF, OF NEW YORK, N. Y., ASSIGNOR TO WESTERN ELECTRIC COMPANY,
INCORPORATED, OF NEW YORK, N. Y., A CORPORATION OF NEW YORK.

AUTOMATIC TELEPHONE SWITCH.

Application filed July 12, 1922. Serial No. 574,387.

To all whom it may concern:

Be it known that I, HAROLD W. GOFF, a citizen of the United States, residing at New York, in the county of New York, State of New York, have invented certain new and useful Improvements in Automatic Telephone Switches, of which the following is a full, clear, concise, and exact description.

10 This invention relates to improvements in switching mechanisms and has particular reference to a switch structure employed in automatic telephone exchange systems.

In the type of switch mechanisms generally known in the telephone art as coordinate switches, a wiping engagement between two sets of contacts has been accomplished by the cooperation of incoming and outgoing line bars and link bars, certain of 20 the line bars being assigned to groups of incoming lines, each line having a set of line contacts, and the link bars being individual to a set of link contacts which are operated to join an incoming line in any 25 particular group to an outgoing line or trunk. In making such a connection the active link contacts and transversely arranged sets of active line contacts are moved relative to each other to bring them into 30 engagement. Each of the incoming line bars being associated with a plurality of incoming lines, participates in the establishment of coexisting connections between the lines of the group to which the line bar is 35 individual and idle outgoing lines or trunks. It is possible that successive operations of 40 said incoming line bars, in establishing coexisting connections, may sometimes tend to disturb said connections by producing noises on the lines and that vibrations of the switching mechanism, due to the establishment of connections, may be imparted to engaged sets of contacts and thereby momentarily interrupt the connections 45 therebetween.

An object of the present invention is to prevent disturbances to existing connections established between cooperating sets of contacts where two active sets of contacts are 50 brought into engagement with each other.

In accordance with the above object, the engagement between two sets of contacts is effected by the operation of a member which is actuated by a latching element controlled by an operating bar and which, after

being actuated to effect engagement between said contacts, is unresponsive to subsequent operations of said latching element while said contacts are in engagement.

Another object is to provide a switch 60 mechanism of simple and economical design which will be effective and reliable in operation.

The above and other objects will appear more clearly from the following detailed 65 description when taken in connection with the accompanying drawing which illustrates some of the mechanical expressions of the inventive idea.

In the drawing, Fig. 1 is a fragmentary 70 front elevation of a switch structure partly broken away and shown in section. Fig. 2 is a fragmentary vertical longitudinal sectional view through the switch structure shown in Fig. 1. Fig. 3 is a view similar to Fig. 2 showing another embodiment of the invention with the parts in normal position, and Fig. 4 is a view similar to Fig. 3 showing the parts in operated position.

Referring to the drawing in detail and more particularly to Figs. 1 and 2, the switch is shown as comprising a plurality of vertically disposed and longitudinally movable line bars 1, some of which may be 75 assigned to groups of incoming subscribers' lines, while others may be assigned to outgoing lines or trunks. Only three of the bars 1 are shown in Fig. 1, but it will be understood that in actual practice a number of these bars will be used commensurate 80 with traffic requirements. Each of the line bars assigned to incoming subscribers' lines serves a group of such lines and after being engaged in the connection of one of said lines to a trunk, may be again employed in the establishment of connections for other lines in the group served by said line bar.

Each of the incoming lines is represented by a set of active contacts comprising four 85 flexible wire conductors 2, but it will be understood that the number of these conductors may be varied in accordance with traffic conditions. The conductors comprising each set of contacts 2 have their rear ends securely mounted in a vertically disposed insulating support 3 and extend outwardly therefrom in a horizontal plane at right angles to the line bars 1. To operate the line bars 1 a magnet 4 is 100 associated with each of said bars and has its 105 110

armature 5 arranged to engage a lug 6 at the lower end of the line bar so that when the magnet is energized, the armature thereof moves the line bar in a downward direction.

Arranged in transverse or intersecting relation to the line bars 1 are a plurality of horizontally disposed link bars 7 pivotally supported on the switch frame 8 by lugs 9 disposed adjacent each end of each of said bars. Each of the link bars 7 is rotated by means of a magnet 10 preferably having its armature 11 forming a part of the link bar.

15 A grid element such as disclosed in my copending application, Serial No. 550,617, filed April 8, 1922, is secured to and extends longitudinally of each of the link bars 7 and comprises an elongated strip 12 of insulated material having series of transverse slots 13 arranged in staggered relation in the opposite longitudinal edges of said strips. These slots are designed to receive four wire conductors 14 which are 20 helically wound about said insulated strip and form a set of active link contacts. The series of slots formed in the upper edge of each insulating strip 12 are also designed to receive the sets of line contacts 2 associated with the link contacts 14 so that the sets of contacts, when moved relative to each other, will be engaged to establish a connection between an incoming line and an outgoing trunk. When one of the link bars 25 7 and its associated set of contacts 14 are employed in establishing a connection, they cannot be again used in making another connection until the first one is released.

Transversely arranged above each set of 30 line contacts 2 and engaging the conductors thereof is a roller 15 which has depending therefrom a substantially U-shaped link-bar-engaging member provided at its lower intermediate portion with an angularly disposed flange 17 designed to be engaged by the rear longitudinal edge of the associated link bar 7 when the member 16 has been rocked in a primary movement and said link bar has been rotated by the energization of 35 its magnet 10. In the uppermost portion of Fig. 2, the member 16 is shown in its normal position; the lowermost portion of said figure shows said member at the termination of its primary movement; and in the middle portion of the figure the member is shown at the termination of its secondary movement after being actuated by the associated link bar 7. When the member 16 assumes these three positions in sequential 40 order, the relative position of the latching member 18 in the slot 19 changes as follows: The end of the latching member in contact with the notch 21 is approximately level with the other end engaged in the slot 19 and any downward movement of

bar 1 will cause the said end in the slot to move downward, but inasmuch as the operating movement of bar 1 is small the resulting movement of the latching member in the slot is also small and no appreciable 70 difference in the relative positions of the latching member in the slot can be noted in Fig. 2 in passing from normal position to the position at the termination of the primary movement. When the secondary 75 downward movement of a latching member is effected, the bar 1 remains stationary and the said latching member is moved to the lowest end of the slot, the other end of the latching member being forced downward 80 from the apex of the notch 21 as shown in the middle portion of Fig. 2.

In order to impart the primary rotary or rocking movement to each member 16, there is preferably provided a latching member 18 consisting of a single length of wire or other flexible material having one end extending rearwardly and mounted in a transversely disposed slot 19 formed in the line bar 1. The intermediate and other end portion of the latching member is bent to form a rectangular frame 20, the upper side of which normally engages in a notch 21 formed in the switch frame to provide a pivot for the latching member and limit the upward movement thereof and of the member 16 when the set of contacts 2 is restored to its normal position upon the disestablishment of a connection. The lower side of the frame 20 is extended through 90 notches 23 formed in the vertical sides of the member 16 adjacent the lower ends thereof so that when the latching member 18 is rocked about its pivot by the actuation of the line bar 1 the pivoted member 105 16 will be given its primary movement to position the flange 17 thereof in the path of movement of the rear longitudinal edge of the adjacent link bar 7.

When a call is initiated on an incoming 110 line in a group served by one of the line bars 1, this bar and another line bar serving an idle outgoing line or trunk are moved downwardly by their respective magnets 4 to actuate the latching members 18 connected to 115 said bars so as to position the members 16 in the path of movement of the link bars 7. Following this operation one of the link bars is rotated about its pivot 9 by the energization of its associated magnet 10 so as to 120 move the set of link contacts carried by said bar relative to two of the sets of line contacts associated with the line bars which have been actuated. As the rear longitudinal edge of the link bar moves downwardly the same contacts the shoulders 17 of the members 16 associated with said two sets of line contacts and upon engagement therewith, forces said members 16 downwardly and exerts a pressure thereon which 125 130

causes the rollers 15 to engage the sets of contacts 2 with the set of link contacts 14. Due to the downward movement of the sets of contacts 2 and the substantially rotary movement of the contacts 14, it will be obvious that a wiping engagement between said sets of contacts will be effected. Continued movement of the link bar 7 to a position shown in the middle of Fig. 2 causes the two sets of contacts associated with the incoming and outgoing line bars to be flexed as shown and by exerting a constant pressure upon members 16 it will be apparent that the sets of contacts 2 and 14 will be maintained in close contacting relation.

After the connection has been established between the two sets of contacts, the magnet 4 individual to the incoming line bar 1 is deenergized to permit of the restoration of the said bar to its normal position so that the same may again be employed in establishing coexisting connections for other lines in the group served thereby. Due to the sliding connection between the rear end of latching member 18 and the line bar 1 produced by mounting the rear end of the said latching member in the slot 19, it will be obvious that the succeeding operations of the line bar will not affect the operated latching member 18 and consequently the existing connection between the sets of contacts 2 and 14 will be undisturbed when the line bar 1 is operated to make other connections.

At the termination of the connection, the link bar 7 is restored to normal by the release of the magnet 10, whereupon said link bar is disengaged from the member 16, and due to the flexed condition of the set of contacts 2, these contacts are permitted to assume their normal positions with the upper side of the frame 20 of the latching member 18 again in engagement with the notch 21.

Referring now to Figs. 3 and 4, the link bar engaging member 24 in this embodiment is shown as pivoted at 25 to an insulated block 26 in which the set of line contacts 2 is embedded, said contacts being also secured in their rear end to the vertical support 3. The lower end of the member 24 is provided with a triangular opening 27 therein designed to receive one extremity 28 of the latching member 29 formed of a single length of wire which is bent at an intermediate portion and at its other extremity about a supporting rod 30 which forms a pivot for the latching member. At 31 the latching member is bent to form an eye or opening for receiving a pin 32 carried by the line bar 1 so that as said bar is actuated downwardly, in the same manner as described in connection with Fig. 2, the latching member 29 is moved about the rod 30 as a pivot. When the member 24 is in its normal position the end 28 of the latching member is positioned in the lower extremity of the opening 27, as shown in Fig. 3, so that when the line bar 1 is actuated to move the rear end of latching member 29 downwardly the end 28 of said latching member will engage the forward edge of the opening 27 and rock the member 24 forwardly about its pivot 25 to substantially the position shown in Fig. 4 with the flange 33 of member 24 in the path of movement of the link bar 7. When this bar is operated in the manner previously described, the grid element carried thereby and including the insulated strip 12 having a set of contacts 14 wound thereon, is moved relative to the set of contacts 2 and at the same time the rear longitudinal edge of the bar 7 is engaged with the flange 33 as shown in Fig. 4, moving the member 24 together with the set of contacts 2 toward the set of contacts 14 until the same are engaged with each other. At this time the set of contacts 2 is flexed as shown in Fig. 4, and a constant pressure is exerted upon said contacts by the bar 7 to maintain said contacts in close engagement. After the contacts have been engaged the incoming line bar 1 is released as previously described and in restoring to its normal position moves the latching member 29 to the full line position shown in Fig. 4. Due to the formation of the opening 27 in the member 24, it will be obvious that the movement of the latching member 29 to its normal position will be relative to said member 24 and therefore said member will be unaffected by the restoration of the latching member. Should the line bar 1 be again operated to establish a subsequent connection while the contacts 2 and 14 are in engagement, the movement of line bar will cause the latching member 29 to assume the dotted line position as shown in Fig. 4. It will again be apparent that this movement of the latching member will not disturb the member 24 due to the formation of the opening 27 therein, and hence succeeding operations of the line bar will have no effect upon existing connections.

At the termination of the connection the link bar 7 is restored to its normal position by the release of its magnet 10 and upon disengaging the flange 33 the member 24 is permitted to restore to its normal position at which time block 26 engages the rod 30. The restoration of link bar 7 and the member 24 separates the sets of contacts 2 and 14 whereupon the same may again be employed in establishing another connection.

What is claimed is:

1. In a switching mechanism, sets of active contacts, a pivotal element associated with said sets of contacts, a pair of operating bars, a latching member loosely connected to said pivotal element and to one of said operating bars, means of operating said operating bar to move said pivotal member into operative relation with the other of said

operating bars, and other means operable to move the second of said operating bars thereby effecting an additional movement in said pivotal member to interconnect said contact sets.

2. In a switching mechanism, sets of active contacts, a pivotal element, a pair of operating bars, an obliquely disposed slot in one of said bars, a latching member, one 10 end of which engages said slot and the other end being loosely connected to said pivotal element, and means associated with one of said operating bars operable to effect a primary of said latching member to move said pivotal element into operable relation with the other of said operating bars, and other means associated with the other of said operating bars operable to effect a secondary movement in said latching member thereby 20 establishing a connection between said sets.

3. In a switching mechanism, sets of active contacts, a pair of operating bars, a pivotal element associated with said sets of contacts, a latching member connected to said pivotal 25 element, an insulating block, a notch in said insulating block, the apex of which notch is used as a pivot for said latching member during its primary movement, and means in said notch for permitting the latching member to slide therefrom thereby releasing the strain on said latching member during its second movement in completing the engagement of said contact sets.

4. In a switching mechanism, sets of active 30 contacts, a pivotal element associated with

said sets of contacts, a flange fixedly attached to said pivotal element, operating bars, a latching member, means associated with one of said operating bars operable to move said latching member which in turn rotates said pivotal element into an operative position, and other means operable to move the other of said operating bars into engagement with said flange to bring both contact sets into engagement. 40

5. In a switching mechanism, a frame a set of active wire spring contacts arranged in a horizontal plane, a set of active helically wound conductors arranged in a vertical plane, a sliding operating bar, a rocking operating bar, a latching member, a pivotal element, a flange fixedly attached to said pivotal element, another flange fixedly attached to said rocking operating bar, means operable to slide first mentioned operating 50 bar thereby moving said latching member to position the said first mentioned flange in operative relation with said second mentioned flange, and means operable to rock the second of said operating bars thereby moving the said set of conductors into an operative position and also moving the attached flange into engagement with the flange on said pivotal member which engagement flexes the said set of wire spring contacts 55 into a wiping connection with the said set of conductors. 60

In witness whereof, I hereunto subscribe my name this 10th day of July A. D., 1922.

HAROLD W. GOFF.
